UNITED STATES PATENT OFFICE.

SAMUEL J. SHERER, OF CHICAGO, ILLINOIS.

DISPLAY-COUNTER.

SPECIFICATION forming part of Letters Patent No. 729,684, dated June 2, 1903.

Application filed April 12, 1902. Serial No. 102,508. (No model.)

To all whom it may concern:

Be it known that I, SAMUEL J. SHERER, a citizen of the United States, residing at Chicago, in the county of Cook and State of Illinois, have invented a certain new and useful Improvement in Display-Counters, of which the following is a specification.

My invention relates to display-counters, and has for its object to provide new and useful improvements more particularly set out in the accompanying drawings, wherein—

Figure 1 is a front view of a portion of such a counter. Fig. 2 is a cross-section on the line 2 2 of Fig. 1. Fig. 3 is a horizontal section on the line 3 3 of Fig. 2. Fig. 4 is a detail end view of the display portion.

Like parts are indicated by the same letter in all the figures.

A is the top; B, the bottom portions. The framework of the entire complete show-case is somewhat similar to other such constructions. There are a series of cross frame-pieces C C, properly dovetailed to receive the cross-plates C' C'. When all of these parts are properly in position, the entire case is divided into a series of longitudinal shelves, so to speak. There are also vertical pieces D D, which go to make up this frame. The outside is preferably paneled, as indicated at D'; but no such panel exists between the several drawers. There is, however, a removable guide-rail E, which is slotted at E' E' to receive the edges of the front and rear vertical pieces D D. Thus the guide-rail is removable, as one end can be raised in the space between the two shelves and the rail be withdrawn when desired. On the inside of the side of the case a somewhat similar guide-rail E² is placed.

E³ is the frame-piece, which receives the side edges of the sections C', being dovetailed like the parts B and on which rests the guide-rails E and on which slides the drawer F.

F is a drawer which is adapted to slide in and out in each shelf-section between the guide-rails E and E². This drawer may be provided with a suitable handle G, which is on the back side or inside of the case. It does not extend the whole distance through the show-case, but leaves a place for the removable display-section. This display-section consists of a glass front J, with the cer-

tain bead-like portion J' J', which portion is adapted to overlap the front case portions J² J². This display-section is provided with a bottom J³ and sides J⁴ J⁴ and a back J⁵.

The front terminating parts of the display-case are so shaped as to leave a lower shoulder at K and an upper shoulder at K'. The sides J⁴ J⁴ of the display-section are downwardly slotted at K², and on the bottoms of these sections J³ are formed the downwardly-projecting stops K³. This permits the display-section to be introduced by inserting the upper end and pushing it up until the shoulder-piece K' comes far down into the slot K², thus bringing it into proper position and dropping it down until the shoulder-piece K is engaged by the stop K³. Here it is properly secured in position without movable parts, hooks, latches, or other such devices. The lower display-section is inclined, as indicated at L, and the bottom proper of the display-counter is extended underneath this inclined portion. Ornamental side sections L' L' are employed; but the forward portion of the lower support of the case B is set well back, as indicated in Fig. 2, so as to leave a substantial recess under the lower show-case section.

It is obvious that this particular illustration of my invention may be considerably altered without departing from the spirit of my invention, and I do not wish to be limited to the identical form of construction shown.

The use and operation will be apparent from what has been already said.

The guide-rail is so arranged that in the event of the same becoming swollen, which often happens when articles of this nature are carried from one climate to another, it can be removed by the owner without any trouble and be then planed down to a size to prevent binding. The display-section is easily put in place or removed, or the sections may be changed from place to place without any difficulty and without having recourse to locks, fastenings, and mechanism which is liable to get out of order. By the arrangement of the lower display-section it can be seen from above, but the woodwork or other ornamental or structural portions of the device at this point are set back, so that they cannot be injured by the toe of the boot

of the person who may be in proximity to the show-case. Such show-cases are often placed where the aisle-space is narrow, and hence the desirability of having the lower display-section inclined; but under these conditions there is also danger of the lower portions or woodwork to the display-section being injured, and hence the desirability of the arrangement which I have shown and which forms part of my invention.

I claim—

1. In a display-counter the combination of a series of shelf-sections for the drawers, with dividing-partitions having openings therein and fixed frame-pieces on which may slide the drawers, and non-elastic guide-rails in the lower part of the openings in said partitions adapted to be removed without disturbing other parts of the counter.
2. In a display-counter the combination of a series of shelf-sections for the drawers, with dividing-partitions having openings therein and fixed frame-pieces on which may slide the drawers, and non-elastic guide-rails in the lower part of the openings in said partitions adapted to be removed without disturbing other parts of the counter, said guide-rails slotted at their ends to receive the edges of the dividing-partitions.
3. In a display-counter the combination of one or more series of shelf-sections; removable display-sections provided with notches in their upper and lower edges into which are

adapted to fit downwardly and upwardly projecting lips to hold said display-section in position, the notches in the upper edge of said display-sections being somewhat deeper than those in the lower edge, thus allowing the display-section to be raised sufficiently to clear the upwardly-projecting lip when it is desired to remove said section, the upwardly-projecting lips occupying the entire depth of the lower notch and supporting the display-section thereby.

4. In a display-counter the combination of one or more series of shelf-sections; removable display-sections provided with notches in their upper and lower edges into which are adapted to fit downwardly and upwardly projecting lips to hold said display-section in position, the notches in the upper edge of said display-sections being somewhat deeper than those in the lower edge, thus allowing the display-section to be raised sufficiently to clear the upwardly-projecting lip when it is desired to remove said section, the upwardly-projecting lips occupying the entire depth of the lower notch and supporting the display-section thereby; and a molding or bead about the display-section adapted to cover up such slots and connections between the display-section and counter proper.

SAMUEL J. SHERER.
